CLAIM

The ornamental design for a window spacer frame locking member, as shown and described.

DESCRIPTION

FIG. 1 is a top left perspective view of a window spacer frame locking member in accordance with the present disclosure;

FIG. 2 is a bottom right perspective view thereof;

FIG. 3 is a right side elevation view thereof;

FIG. 4 is a left side elevation view thereof;

FIG. 5 is a front elevation view thereof;

FIG. 6 is a rear elevation view thereof;

FIG. 7 is a top plan view thereof;

FIG. 8 is a bottom plan view thereof;

FIG. 9 is a cross-section of a right side elevation view thereof taken along lines 9-9 of FIG. 1; and,

FIG. 10 is a cross-section front elevation view thereof taken along lines 10-10 of FIG. 1.

1 Claim, 10 Drawing Sheets
